ELECTROOPTICAL SYSTEM

John J. Rogan, Elmhurst, N. Y., assignor to Hy-grade Sylvania Corporation, Salem, Mass., a corporation of Massachusetts

Application November 22, 1929, Serial No. 409,005

9 Claims. (Cl. 178—6)

This invention relates to electro-optical systems and with particularity to methods and means for translating currents into visual representations.

5 The invention is in the nature of an improvement on the type of system disclosed in copending application of John J. Rogan, Serial No. 409,002, filed Nov. 22, 1929. There is disclosed in said application a system of television wherein 10 two separate light sources are employed at the receiving station, one of constant and high intensity, and the other of varying intensity. The principal object of the present invention is to provide a novel arrangement of lights at the 15 receiving station of a television system whereby greater apparent contrast is secured between the light and dark areas of the reproduced image.

Another object of the invention is to provide a novel method of combining the effects of a constant intensity light source and a varying intensity light source in the reproduction of a visual representation by electricity.

A feature of the invention relates to a system of reproducing visual representations at a distance wherein reproducing light sources of different colors or wave-lengths are employed.

A further feature of the invention relates to a system of reproducing visual representations at a distance wherein reproducing lights having complementary color characteristics are employed.

A still further feature relates to the organization and arrangements of parts which go to make up an efficient television or picture transmission system and wherein for a given transmission level, more pronounced visual effects are produced at the receiving station.

Other features and advantages not specifically enumerated will be apparent after a consideration of the following descriptions and the appended claims. While the features and objects of the invention will be disclosed in connection with certain well-known types of apparatus, it will be understood that the invention is not limited thereto but that this apparatus is used merely for the purpose of illustrating preferred modes of carrying out the inventive concept. Accordingly,

Fig. 1 of the drawing illustrates in diagrammatic fashion one manner of reproducing visual representations according to the invention.

Fig. 2 shows a modified form of reproducing system.

Fig. 3 shows a still further modification of the system disclosed in Fig. 1.

Referring to Fig. 1, there is shown in diagrammatic form a reproducing arrangement suitable for a television system wherein the numeral 1 represents a light source which is adapted to have its intensity varied in accordance with image currents received over the transmission channel 5. For example, one known type of lamp suitable for this purpose includes a pair of spaced electrodes enclosed within an atmosphere of neon, which when excited gives off a pinkish-red 10 color. The light from lamp 1 is projected by means of a suitable optical system 3 upon a suitable surface 4 such as a ground glass screen, which may be viewed from either the front or rear sides, preferably the latter. The illuminated 15 field is represented in Fig. 1 by the dotted square 5, which may be of any size consistent with the detail required and the intensity of illumination from lamp 1.

As the varying image currents act upon lamp 1, 20 there is projected upon the screen 4 a light spot of uniform dimensions, but of an intensity or light distribution varying in accordance with the image currents. In the case of a neon lamp the screen will therefore appear to be illuminated 25 with a pinkish-red color.

Situated on one side of the screen 4, preferably on the same side as lamp 1, although this is not absolutely necessary, is a source of light 6 of constant and preferably high intensity such as 30 an arc lamp or the like. The light from lamp 6 is projected by a suitable optical system 7 upon a portion of the periphery of scanning disc of the usual or Nipkow type, although a lens disc of the type shown in Jenkins Patent No. 1,679,086 may 35 be employed. When the disc is not interposed between the light 6 and screen 4, the light from lamp 6 is so adjusted as to produce a light field of the same dimensions as that produced by lamp 1. However, when the disc is interposed and rotated 40 in synchronism with a corresponding analyzing device at the sending station in the well known manner, the light from lamp 6 covers the field 5 in the form of a rapidly moving spot, which however due to its rapidity causes the field apparently 45 to be entirely illuminated.

As is well known, the light from a neon lamp has a characteristic color which for certain purposes may be undesirable or even tiresome. In order to overcome these and other defects, and 50 at the same time increase the apparent contrast between the picture field background and the reproduced images, it is preferable to so modify the constant intensity light from source 6 so as to make it complementary to that from source 1. 55

Thus if a filter is interposed at the point 9, so that blue light reaches the screen from source 6, this moving spot of blue light will combine with the reddish-like light from source 1 to produce a more nearly white spot. The image will therefore be produced in the form of a moving spot varying between white and red, the normal color of the light source 1.

It will be understood that if the screen 4 is viewed by reflected light, it must be capable of reflecting substantially all the rays from sources 4 and 5, although it may be prepared to act as a selective reflector so far as the light from source 6 is concerned.

Furthermore, while a neon lamp or reddish light is used for source 1, it will be understood that any other color of light may be employed so long as it is complementary, or at least combines with the light from source 6 to heighten the apparent contrast of the reproduced image.

Referring to Fig. 2, there is shown another manner of combining the light sources. Numeral 10 represents a source of light, preferably of high and constant intensity, the rays of which are projected through the scanning disc 11 by a suitable optical system. Positioned on the opposite side of the disc is a glow discharge lamp-screen 12 of the type disclosed in co-pending application

Serial No. 409,004. Located in front of screen 12 is a suitable optical system through which the observer may view the light from source 10 as well as the light from lamp-screen 12. As pointed out in the above-noted application, the observer receives the sensation of movement from the source 10 (through the intermediary of disc 11) and also a sensation of varying brilliancy due to the lamp 12 which is energized under control of the incoming image currents. In order that the apparent brilliancy or heightened contrast may be achieved it is preferred to so design the lamp screen 12 either by the gas content voltage, etc., that the rays therefrom are complementary to those emitted by the source 10. Thus if a neon gas content is employed for lamp 12 and lamp 10 emits rays near the blue end of the spectrum, the image will appear in the form of variations between white and red or orange, whereas in the ordinary system using a single light source the variation is between different brilliances of the same color. It will be understood of course that any other combination of light sources may be employed.

Fig. 3 shows a still further arrangement for practicing the inventive concept. In this embodiment the source 13 corresponds to the sources 6 and 10 (Figs. 1 and 2) and disc 14 is similar to discs 8 and 11. The incoming image currents however (after being suitably amplified) are applied to a lamp 15 which gives forth rays complementary to those from source 13. Interposed between the observing optical system 16 and the disc 14 is a so-called "transparent-mirror" or total reflecting prism 17. Since the source 13 is in alignment with the optical system 16, the rays therefrom may be seen directly through mirror 17, while the rays from source 15 reach the observer's eye by reflection from mirror 15. There is thus produced a combined visual sensation of movement and varying intensity using complementary color sources.

While only three modes of combining the light

sources are illustrated, it will be understood that the invention is not limited thereto, but relates to any equivalent method of such combination.

What is claimed is:

1. Means for reproducing visual representations at a distance including a picture receiving screen, a spot of light of constant intensity, means for moving said spot over said screen to scan the same, a stationary light of different color from the first light, means for varying only said stationary light by received image currents while maintaining the first light constant, and means for optically and concurrently combining both said lights, the last-mentioned means including a screen to which both lights are separately and simultaneously applied. 5

2. Means according to claim 1 in which both said lights are complementary in color.

3. The method of television which comprises producing a stationary reddish light beam, simultaneously and separately applying to a screen together with said reddish beam a beam from another source of a color complementary thereto, moving one of said beams over a screen to scan the same, and varying the intensity of only the 20 stationary beam in accordance with received image currents while maintaining the other beam constant. 25

4. Means for reproducing visual representations at a distance including a stationary light beam, a movable light beam, said light beams being of different wave-bands, means for varying only one beam by received image currents while maintaining the other beam substantially constant and means for optically combining said 30 beams, the last-mentioned means including a screen to which both beams are simultaneously and separately applied. 35

5. Means according to claim 4 in which said light beams are substantially complementary. 40

6. Means for reproducing visual representations at a distance including a moving light spot of constant intensity, a stationary light spot of different color from the moving spot, means for varying only one spot by received image currents 45 while maintaining the other spot substantially constant and means for optically and concurrently combining said spots, the last-mentioned means including a screen to which both spots are simultaneously and separately applied. 50

7. Means according to claim 6 in which said spots are substantially complementary in color.

8. In an image reproducing system, a moving light spot, a stationary light spot, means for controlling one of said spots by received image currents, and means including a transparent mirror for optically combining said spots. 55

9. In an electro-optical system employing a scanning device the method of producing an image under control of received image currents 60 which comprises illuminating an entire translucent screen with a stationary artificial beam, simultaneously and separately illuminating said screen with another beam of elemental cross section and constant intensity, moving the last mentioned beam in a point by point fashion to cover the entire screen, and simultaneously varying the intensity of the first mentioned beam under control of received image currents. 65

JOHN J. ROGAN.
